UNITED STATES PATENT OFFICE

ADOLPH A. THOMAS, OF NEW YORK, N. Y.

ELECTRIC PHONOGRAPH

Application filed February 1, 1927. Serial No. 165,052.

My invention relates to electric phonographs, and its object is to provide a hoñless instrument of novel construction and improved operation. As will appear later, my 5 invention finds special utility in electric phonographs of the portable type, producing a small instrument capable of great volume and good quality of tone.

One of the main features of my invention 10 is a loudspeaking unit consisting, in its preferred form, of two flat diaphragms adapted to accentuate different bands of frequencies, so as to encompass practically the entire range of audible sound. These diaphragms 15 are in the form of tensioned sheets mounted in close parallel relation on a flat frame, which is so pivoted as to be raised into upright position for operation of the dia- phragms. When the lid of the machine is to 20 be closed, the diaphragm-supporting frame is lowered into horizontal position, where it occupies a shallow space adjacent the lid. In a preferred embodiment of my invention, the frame that carries the two diaphragms 25 is automatically raised and lowered by the opening and closing of the lid.

In the construction of a portable electric phonograph according to my invention, the carrying case is constructed of two shallow 30 box-like sections arranged to provide two compartments side-by-side. One compartment is for the phonographic mechanism (that is, the driving motor, turntable and electric reproducer), and the other compart- 35 ment contains the double loudspeaker unit and all or some of the electric parts (namely, batteries, transformers, vacuum tubes, etc.) that comprise the amplifying transmission system employed. Some of these electric 40 parts may be mounted in the phonograph compartment, if necessary or preferred. The arrangement of the two compartments side- by-side permits the use of a shallow case or 45 box that is easily carried about and put out of the way. The carrying case may be made permanently flat like a man's suitcase, or the two compartments may be so hinged together that one folds over the other. In the latter 50 modification, the case when closed has a cubi-

cal shape, but when open it is flat like the suitcase construction.

In order to explain my invention so that those who are skilled in the art may understand and use the same, I shall describe in 55 detail the two embodiments shown in the accompanying drawings, in which—

Fig. 1 shows a cross-sectional front view of a portable electric phonograph constructed in accordance with my invention, the lid of 60 the carrying case being shewn in closed position;

Fig. 2 is a transverse sectional view of Fig. 1, with the lid and loudspeaker unit in raised position;

Fig. 3 shows a front view of the machine with the lid open as in Fig. 2;

Fig. 4 is a fragmentary plan view showing a suitable mounting for the electric repro- 70 ducer on the motorboard;

Fig. 5 is a perspective view of the closed carrying case in which all the parts of the machine are contained;

Fig. 6 shows a cross-sectional front view of a modified construction of portable elec- 75 tric phonograph, in which the carrying case consists of two sections hinged together trans- versely;

Fig. 7 is a transverse sectional view on line 6—6 of Fig. 5;

Fig. 8 illustrates a cross-section through the carrying case when closed;

Fig. 9 illustrates, in reduced perspective, the carrying case of Figs. 5—7 in closed condition;

Fig. 10 shows in plan view the double- diaphragm loudspeaking unit embodied in the machines of Figs. 1—8;

Fig. 11 is a fragmentary detail to show a face view of the magnet associated with the 90 driving units of Fig. 10; and

Fig. 12 is a diagram of an amplifying sys- 95 tem for operatively connecting the electric reproducer with the driving units of the loud- speaking mechanism.

Referring to the construction shown in Figs 1—4, there is a carrying case K which has the general shape and appearance of a suitcase. The outer structure of the case comprises a main section or body 10 and a 100

lid 12 hinged at 13 to the rear edge of the main section. The shallow box-like section 10 is preferably provided with a transverse partition 14 to increase the rigidity of the case. In that event, the lid 12 may have a transverse strip 15 arranged to rest on the top of partition 14 when the lid is closed, as shown in Fig. 1.

The transverse partition 14 divides the case into two compartments 16 and 17 arranged side-by-side. The right compartment 16 contains the phonographic mechanism of the machine, and I shall therefore call it the phonograph compartment. In this compartment is a motorboard 18 carrying a driving motor 19, a turntable 20, and an electric reproducer 21. The motor 19 may be either electrical or mechanical. If the motor is mechanical, a winding crank 19' is adapted to be inserted into the right end of the case for winding the motor springs. If the motor is electrical, it may be operated by a battery in the carrying case, or by plugging into an electric light socket. Since phonograph motors, both electrical and mechanical, are well known in the art and may be obtained in the market, it will not be necessary to show or describe any structural details of motor 19. The electric phonograph reproducer 21 is of any approved construction, either of the microphone or the electromagnetic type, and is so mounted as to move horizontally over a record. Since my invention is not limited to any particular form of electric reproducer, and since various constructions of electric reproducers are well known in the art, I need not encumber this description with the details of reproducer 21. It is sufficient to mention that the reproducer 21 is carried by an arm 22 pivoted at 23 for vertical and horizontal movement in the playing of a record. When the reproducer is not in use, the arm 22 is swung aside and clamped in position by spring fingers 24 projecting upwardly from the motorboard, or by any other practical supporting means.

The top space of the phonograph compartment 16 may be utilized to house a stack of records 25, which are secured to the inside of lid 12 in any practical way. In the drawings I have shown the records strung on a peg 26 to which they are secured by a wing-nut 27 and a clamping disk or washer 28. In Fig. 1 I have shown three 12-inch and three 10-⁵⁵ inch records supported by the lid. The records do not interfere with the closing of the lid when the reproducer arm 22 is held in rest position on support 24.

The compartment 17, which occupies the left half of the carrying case, contains my new loudspeaking mechanism and preferably also some or all of the electric parts that constitute an amplifying transmission system between the electric reproducer and the loudspeaking mechanism. A top board or cover

plate 29 divides the compartment 17 into upper and lower chambers. In the lower chamber are mounted one or more batteries 30, one or more audio-frequency transformers 31, one or more amplifying vacuum tubes 32, and other parts, such as condensers, rheostats, potentiometers, etc., that may be necessary to complete any desired form of transmission system. The cover 29 is hinged at 33 and rests on strips 34 secured in compartment 17. A suitable latch 35 engages the front edge of cover 29 to hold the same locked in closed position, and a finger piece 36 makes it easy to lift the cover for access to the electrical parts beneath.

My new loudspeaking mechanism is indicated as a whole by L and in its preferred form is constructed as follows, special reference being had to the enlarged view of Fig. 10. A pair of loudspeaking diaphragms 37 and 38 are stretched on opposite sides of a flat rectangular frame F, which in the present instance consists of a board or panel 39 carrying a pair of tubular side pieces 40. These side pieces may conveniently be formed from sheet metal and secured to the board 39 by suitable fastening devices 41, which may be screws, bolts, rivets, or the like. If desired, the flanged end portions of the side pieces 40 may be secured together at 41' to increase their rigidity. The diaphragms 37 and 38 are secured to the side pieces 40 by resilient clamping strips 42 which are attached to the side pieces by screws 43 or otherwise. The clamping strips 42 are preferably formed with roughened engaging surfaces 42' adapted to grip the ends of the diaphragm against all possibility of slipping. Any other practical means may be employed for securing the diaphragms 37 and 38 to the frame F. The diaphragms 37 and 38 are made of elastic sheet material and are corrugated so as to be held under constant tension of the required degree. In other words, the diaphragms are stretched across the frame F with such tautness that they vibrate properly with substantially equal amplitude over their acoustic surfaces. This free vibration of the diaphragms is due to the fact that they are attached at two edges only, leaving the opposite edges 44 and 45 free or floating.

In the broad aspect of my invention, the two diaphragms 37 and 38 may be duplicates of each other and have substantially the same natural frequency. However, at the present time I prefer to construct the diaphragms so as to accentuate different bands of frequencies. That is to say, one diaphragm is adapted to operate most efficiently in the upper register, while the other diaphragm operates with best results in the lower register, so that the entire range of audible frequencies is reproduced with equal fidelity, or as nearly so as mechanical and electrical conditions permit. In Fig. 10 I

have assumed that the diaphragm 37 accentuates the upper register and the diaphragm 38 the lower register. For convenience I shall therefore refer to diaphragm 37 as the high diaphragm, and the 5 diaphragm 38 I shall call the low diaphragm. These diaphragms may be made of the same material, but of such dimensions or weight as to have different acoustic capacities. 10 Among materials suitable for the construction of these diaphragms, I may mention steel, iron, duralumin (an aluminum alloy), copper, bronze, celluloid, paper, wood, parchment, and others along the same line. 15 The diaphragm 37, for example, may be of elastic sheet metal having a high natural frequency and capable of correctly reproducing the higher notes of the piccolo and violin, and the diaphragm 38 may consist of 20 a non-metallic sheet having a low natural frequency and capable of reproducing the deepest organ tones. The acoustic area of 25 the diaphragms is such that the resultant reproduction has a volume equal to (and in some instances greater than) that given out by large cabinet phonographs of prior construction.

The loudspeaking diaphragms 37 and 38 are operated by electromagnetic driving 30 units mounted on opposite sides of the board 39. These driving units, which are indicated as a whole by M and M' in Fig. 10, may be of any practical construction. By way of example and not as a limitation, I have 35 shown a driving unit consisting of a permanent magnet 46 having a coil or coils 47 mounted on pole pieces 48. As shown in Fig. 10, the magnets 46 of the driving units are mounted in alignment on opposite sides 40 of the board 39, so that the same set of screws or bolts 49 hold both magnets in position. The diaphragm 37 is provided with an armature 50 adjacent the polar ends of the associated magnet. Similarly, the other diaphragm 38 has an armature 51 in operative 45 relation to the pole pieces of its driving unit. If the diaphragms 37 and 38 are of magnetic material, no separate armatures are necessary. Instead of having a magnetic 50 connection between the diaphragms and their driving unit, the construction of the latter may be such as to require a mechanical connection between the diaphragms and the vibratory armature of the unit. Such driving 55 units are well known in the art and need not be illustrated. It will therefore be understood that the driving units M and M' shown in the drawings are to be regarded as broadly representing any practical form 60 of mechanism for operating the diaphragms in accordance with current impulses generated by the electric reproducer of the machine. For convenience, I shall call the windings 47 of unit M as the controlling coil 65 of diaphragm 37, and the windings 52 of

unit M' will be referred to as the controlling coil of diaphragm 38.

The board 39 of the loudspeaking mechanism is preferably solid so as to separate the diaphragms 37 and 38 acoustically. These diaphragms form a pair of shallow sound 70 chambers 53 and 54, which are freely open to the outer air at the top and bottom. During the operation of the diaphragms, the air columns in sound chamber 53 and 54 are set in vibration, whereby the sound produced by the diaphragms is augmented in volume. Since the sound chambers 53 and 54 are separated by the board or panel 39, there is 75 no interference between the vibrations produced behind the diaphragms. The board 39, which is substantially free of vibration, 80 may be of light rigid metal, such as aluminum or aluminum alloy, or it may be of non-metallic material, such as wood, hard rubber, bakelite and similar materials adapted 85 for this purpose.

The unitary loudspeaking mechanism L is hinged at 55 to a strip 56 fastened along the rear edge of compartment 17, as shown 90 in Fig. 2. The board 39 is connected at its upper end to the lid 12 by a chain or strong cord 57. One end of this chain is attached at 58 to board 39, and the other end of the chain is connected to a flat helical spring 59 secured to the inside of cover 12. The hinge 55 is formed with a bracket 60, which acts as a stop for the board 39 when the same is in upright position, as illustrated in Fig. 2. The spring 59 renders the connection 57 sufficiently elastic to prevent any undue strain at hinge 55. The lid 12 is held in open position by one or more collapsible braces 61 of usual construction. These braces, which act 100 like toggles, hold the lid propped open in such position that the loudspeaking mechanism L is automatically maintained in upright position when the lid is open. As seen in Fig. 2, the open lid deflects forwardly the sound waves that strike it from the rear diaphragm, thereby amplifying the reproduction. Instead of using the flexible connection 105 57 and brace 60 to hold the loudspeaking mechanism in upright position, I may use a rigid collapsible brace like 61, or any other 110 practical arrangement. Upon closing the lid, the mechanism L is automatically lowered into horizontal position, as shown in Fig. 1. When these parts are in closed position, the free edge of board 39 rests on a ledge 62 provided near the top of chamber 17. The lid 12 has a strip 63 arranged to engage the front edge of board 39 when the parts are in closed position. This is indicated in dotted lines 115 in Fig. 2, where it will be seen that the loudspeaking mechanism is held against movement by means of the strips 62 and 63 lying on opposite sides of the board 39. The case may therefore be transported without any 120 danger of injury to the loudspeaking mech- 125 130

anism. The flexible connection 57 does not interfere with the proper closing of the lid.

The loudspeaking mechanism L is of such flat construction as to fit in the shallow space 64 between the lid 12 and cover plate 29. The thickness of mechanism L need not be more than one inch, and may even be less in small machines. We thus have a double diaphragm loudspeaker capable of giving tremendous 10 volume and yet one that can be accommodated in a carrying case of small dimensions. In the broad view of my invention, the loud-speaking mechanism need not be attached to the lid 12 for automatic raising and lowering by the movements of the lid. This mechanism may be mounted in any other practical way so as to lie normally within the casing and to be raised into operative position.

In the modified construction of Figs. 6-9, 20 the carrying case K' consists of two box-like sections 65 and 66 hinged together at 67 and forming when open two shallow compartments side-by-side. The section 66 contains the phonographic mechanism indicated as a 25 whole by P and which may be the same as the mechanism in compartment 16 of Fig. 1. The section 65 contains the loudspeaker mechanism L and the electric parts that constitute the amplifying transmission system 30 between the electric reproducer and the loud-speaking diaphragms. In the drawings I have shown a pair of vacuum tubes 68 and an amplifying transformer 69 mounted horizontally in chamber 70 of section 65. It will 35 be understood that the parts 68 and 69 do not form the complete transmission system, but are merely indicated by way of example to show how such parts are housed in the carrying case. The chamber 70 is closed by a cover 40 plate 71 hinged at 72. What has been said about cover plate 29 in Figs. 1 and 2 applies fully to cover plate 71 without the need of repetition.

The loudspeaking mechanism L in Figs. 45 6-9 is hinged at 73 to a strip 74 in section 65. A strip 75 forms a stop for the mechanism L when the same is raised in vertical position, as will be understood from Fig. 7. To hold the mechanism in upright position, the board 50 39 is provided near its lower end with a latch-bar 76 pivoted at 77 and provided with a forwardly projecting lug 78. On one of the strips 79 that support the cover plate 71 is mounted a locking finger 80. After the mechanism L has been swung into upright position, the latch-bar 76 is turned down until the lug 78 engages the spring finger 80, as 55 shown in Fig. 6, whereby the loudspeaking unit is securely locked in upright position. A finger piece 81 near the free edge of board 39 permits the latter to be readily grasped by the hand for manipulation. When the mechanism L lies flat in the case-section 65, the front edge of board 39 rests on a strip 82. 60 A latch 83 locks the board 39 in lowered position.

tion, so that the box sections 65 and 66 can be folded together to close the case without injury to the loudspeaking mechanism. This will be clear by looking at Fig. 8.

In order to accommodate a stack of records in the carrying case K', I provide the phonograph section 66 with strips 84 along the top. I have already said that the loud-speaker section 65 has a strip 75 which forms a stop for the board 39. The strip 75 runs around the section 65 about half-way between the cover plate 71 and the top edge of the section. When the two sections 65 and 66 are closed, as shown in Fig. 8, the strips 75 and 83 provide a space for receiving a 75 tray or shallow box 85 adapted to contain a 80 set of records 86. When the carrying case K' is closed, the record box 85 is securely held in position by and between the strips or flanges 75 and 83. The case K' is easily carried about by providing each section 65 and 66 with a handle 87. Suitable locks 88 hold the closed sections locked.

The carrying case K', when closed, is cubical in shape and in that respect it differs from the carrying case K of Fig. 5. When the sections 65 and 66, however, are in open position, as shown in Fig. 6, the machine is flat like that in Figs. 1-3. In either construction we have a carrying case of comparatively 95 small dimensions. To give an idea of the compactness of my new machine, I may mention that the carrying case in Figs. 1-5 is about twenty-six inches long, thirteen inches deep and about five inches high. The cubical case of Figs. 6-9 is about thirteen inches long, thirteen inches deep and eight or nine inches high. The diaphragms of the loud-speaking mechanism L in the embodiments 100 illustrated are about ten inches high and eleven inches wide. These figures, of course, are given merely by way of illustration and are not intended to operate as limitations of the invention. The size, shape and style of the carrying case may be so selected by the 110 builder as to suit his particular taste, or what he thinks the public would like best.

Any practical system may be adopted for amplifying and transmitting the electric impulses of the reproducer to the operating or 115 controlling coils of the diaphragms. An example of such an amplifying transmission system is diagrammatically illustrated in Fig. 12. The operating coils 47 and 52 of the loudspeaking mechanism are connected in 120 parallel to the secondary winding 89 of an audio-frequency transformer T. In the circuit of coil 47 is a variable inductance 90, and in the circuit of coil 52 is a variable inductance 91. These inductances are so adjusted 125 in value as to cause the diaphragms 37 and 38 to give the best acoustic results. It has been previously assumed that diaphragm 37 operates most efficiently on high notes, and diaphragm 38 is best on low notes. In that 130

case the inductance value of the circuit of coil 52, which operates the low diaphragm 38, should preferably be greater than the inductance value of the circuit of coil 47 which operates the high diaphragm 37. The relative inductance values of the circuits of loud-speaker coils 47 and 52 are adjusted by means of the variable inductance windings 90 and 91, as will be clear to those who are familiar with this branch of electrical engineering. The primary coil 92 of transformer T is connected in the plate circuit of an amplifying tube V, which is of usual construction, having a filament 93, a grid 94 and a plate electrode 95. The plate battery 96 is connected in circuit in the usual way, and the filament 93 is fed by a battery 97. Between the electric reproducer 21 and the grid 94 of the vacuum tube is interposed a transformer 20 T' having a primary winding 98 and a secondary winding 99. One end of the secondary winding 99 is connected to the grid 94 and the other end is connected to a conductor 100, which is connected to one side of the filament 93. The primary winding 98 is in the circuit of reproducer coil 101, in which the stylus vibrations induce electric impulses.

It will be understood from the preceding description of Fig. 12 that the electric impulses in reproducer coil 101 are transmitted in greatly amplified form to the secondary winding 89 of transformer T, and these amplified impulses pass through coils 47 and 52 for operating the loudspeaking diaphragms 37 and 38. Although I have shown only one stage of vacuum tube amplification, it will be understood that several stages may be employed. Any other practical transmission system may be connected between the reproducer and the diaphragm coils. If the electric reproducer 21 is of the microphone type, it is usually sufficient to have one or two amplifying transformers without vacuum tubes.

45 In a portable self-contained machine, all the parts of the amplifying system used are mounted in the case, but in the broad aspect of my invention as embodied in a semi-portable or larger household cabinet, the amplifying system connecting the reproducer to the driving unit of the loudspeaker may be partly contained within the case or cabinet and partly outside thereof. Some amplifying systems might be too heavy for installation in portable phonographs, and it might therefore be more convenient to use a separate amplifier, especially if the machine is in a home that has a radio set. The chambers 17 and 70 may be used for housing any suitable loudspeaking 50 mechanism, with or without parts of an amplifying system, depending on the design and dimensions of the case.

Although I have shown and described certain constructions, I want it understood that 55 my invention is not limited to the details set

forth. The specific structures illustrated in the drawings are to be regarded merely as practical examples of my invention, which may be embodied in other ways than herein described. The case or cabinet containing the parts that constitute the complete phonograph need not be of the portable type, but may be constructed as a piece of household furniture. I have shown portable cases merely to emphasize the fact that my invention finds special utility in portable electric phonographs, which are particularly desirable by people living in city apartment houses where the rooms are usually small. My new invention may also be constructed as a so-called table machine, which is not intended to be transported like a piece of hand luggage, but which is placed on a table for playing and may easily be carried about the house from one room to the other.

70 My new double diaphragm loudspeaker unit may obviously be used for radio reproduction, and in other connections where loud-speaking reproduction is desired. On account of an official requirement of division, I 75 do not herein make any claims to the loud-speaker unit per se, which forms the subject matter of at least one divisional application.

80 I claim as my invention:

1. A portable electric phonograph comprising a carrying case constructed of two shallow box-like sections arranged to provide two compartments side by side, phonographic mechanism in the compartment of one section, said mechanism including an electric reproducer, a flat frame pivotally mounted on the other section of the case so as to swing into upright position, a loudspeaking diaphragm and a driving unit therefor mounted on said frame, electric transmission apparatus in the 90 compartment of said other section and operatively connected to said reproducer and driving unit, releasable means on said case for rigidly holding said frame in raised position during the operation of said diaphragm, said frame and the parts carried thereby being adjustable into horizontal position in said other section to permit closing of the carrying case, and means for closing said box-like sections to form a completely closed case.

95 2. A portable electric phonograph comprising a substantially rectangular carrying case having a transverse partition to provide two box-like sections side by side, a lid hinged to said case to cover both sections and thereby 100 form a completely closed carrying case, phonographic mechanism in one of said sections, said mechanism including an electric reproducer, a frame pivoted to the other section so as to be moved into upright and horizontal position, a loudspeaking diaphragm and a driving unit therefor mounted on said frame, electric transmission apparatus in said other section for operatively connecting said reproducer with said driving unit, and means 105 110 115 120 125 130

whereby said lid when open holds said frame firmly in upright position during the operation of said diaphragm, said frame and the parts carried thereby being movable into horizontal position in said other section to permit closing of said lid.

3. A self-contained portable electric phonograph comprising a carrying case constructed of two shallow box-like sections arranged to provide two compartments side by side, phonographic mechanism in the compartment of one section, said mechanism including an electric reproducer, a movable cover mounted on the other section to close the compartment thereof, electric apparatus mounted in the last-named compartment, a flat frame pivoted to said other section above said movable cover, a tensioned loudspeaking diaphragm sheet stretched on said frame, a driving unit for said diaphragm also mounted on said frame, means on said other section adapted to engage said frame and normally hold the same within said section parallel to said cover, said frame and the parts carried thereby being movable into substantially upright position for operation of the diaphragm, means for so connecting said apparatus that the electric impulses of said reproducer are amplified and transmitted to said driving unit, releasable means on said case for rigidly holding said frame in raised position during the operation of said diaphragm, means whereby said box-like sections are closable to form a completely closed case, and means for supporting a stack of records in the closed case, said records being automatically rendered accessible when the case is opened.

4. A self-contained portable electric phonograph comprising a substantially rectangular carrying case having a transverse partition to provide two flat box-like sections side by side, a lid hinged to said case to cover both sections and thereby form a completely closed carrying case, phonographic mechanism in one of said sections, said mechanism including an electric reproducer, a cover hinged to the other section below the top edge thereof to form a normally closed compartment, electric apparatus mounted in said compartment, a flat frame pivoted to said other section above said cover, a loudspeaking diaphragm and a driving unit therefor mounted on said frame, said diaphragm consisting of a tensioned sheet stretched across said frame, means for so connecting said apparatus that the electric impulses of said reproducer are transmitted to said driving unit, said frame and the parts carried thereby being movable into substantially upright position for operation of the diaphragm and movable into horizontal position closely above said cover to permit closing of the lid, means whereby said frame is held against movement when the lid is closed, and means on said lid for supporting a stack of records above the motor-

board in the phonograph section of the case.

5. A hornless electric phonograph comprising a cabinet having a lid, loudspeaking mechanism supported in said cabinet independently of said lid, said mechanism being a flat unit having a pair of diaphragms constructed to accentuate different bands of frequencies so as to cover practically the whole range of musical sound, means carried by said casing for adjustably supporting said flat unit to permit closing of the lid, and electric reproducing means for simultaneously operating said diaphragms.

6. A portable electric phonograph comprising a carrying case provided with a hinged cover, a frame pivoted to said case and normally lying flat therein to permit closing of the cover, said frame being movable into substantially upright position, a pair of loudspeaking diaphragms carried by said frame, electric reproducing mechanism for operating said diaphragms, and means connected to said cover for holding said frame in upright position during the operation of the diaphragms.

7. An electric phonograph comprising a case having a top lid hinged thereon, a frame pivoted to said case independently of said lid and normally lying flat in said case beneath the lid, a loudspeaking diaphragm carried by said frame, means for automatically raising said frame into substantially upright position when the lid is opened and holding the frame in such position, said frame automatically moving into horizontal position when the lid is closed, and electric reproducing mechanism for operating said diaphragm.

8. An electric phonograph comprising a case having a top lid hinged thereon, a frame pivoted to said case independently of said lid and normally lying flat in said case beneath the lid, a loudspeaking diaphragm carried by said frame, a collapsible connection between said frame and said lid for automatically raising the frame into substantially upright position when the lid is opened, said connection permitting the frame and the lid to swing down on their respective pivots into horizontal position, and electric reproducing mechanism for operating said diaphragm.

9. A portable electric phonograph comprising a carrying case having two shallow box-like sections arranged side by side, phonographic mechanism in one section, said mechanism including an electric reproducer, electric loudspeaking mechanism in the other section operatively connected to said reproducer, and means for closing said box-like sections to form a completely closed case, said loudspeaker mechanism being a flat hornless structure with a direct-acting diaphragm and arranged to permit closing of the case.

10. A portable electric phonograph comprising a carrying case having two shallow box-like sections arranged side by side, phono-

graphic mechanism in one section, said mechanism including an electric reproducer, electric loudspeaking mechanism in the other section operatively connected to said reproducer, 5 means for closing said box-like sections to form a completely closed case, said loudspeaker mechanism being a flat hornless structure with a direct-acting diaphragm and arranged to permit closing of the case, and means in 10 one of said sections for supporting a stack of records without interfering with the closing of the case.

11. A portable electric phonograph comprising a substantially rectangular carrying 15 case having a transverse partition to provide two box-like sections side by side, a lid hinged to said case to cover both sections and thereby form a completely closed carrying case, phonographic mechanism in one of said sections, 20 said mechanism including an electric reproducer, a frame pivoted to the other section so as to be moved into upright and horizontal position, a loudspeaking diaphragm and a driving unit therefor mounted on said frame, electric 25 transmission apparatus in said other section for operatively connecting said reproducer with said driving unit, and releasable means for bracing said frame in upright position in front of the open lid during the operation of said diaphragm, said lid acting as 30 a deflector of sound produced by said diaphragm, said frame and the parts carried thereby being movable into horizontal position in the case to permit closing of the lid.

35 12. A self-contained portable electric phonograph comprising a pair of flat box-like sections hinged together transversely so as to fold against each other to form a closed carrying case, phonographic mechanism in one 40 section, said mechanism including an electric reproducer, loudspeaking mechanism in the other section, means for transmitting the electric impulses of said reproducer to said loudspeaking mechanism, said phonographic 45 mechanism and loudspeaking mechanism being so arranged as to leave a shallow space or chamber between them when the sections are closed, and means for supporting a record-holding tray or box in said shallow chamber.

50 ADOLPH A. THOMAS.
